UNITED STATES PATENT OFFICE.

CESARE C. CAMPUS, OF SANTA MONICA, CALIFORNIA.

FLUID-TRANSFER DEVICE.

Application filed July 30, 1926. Serial No. 125,850.

This invention relates to a fluid transfer device and more particularly to what may be termed a thermo manually indicative transfer valve. As herein illustrated, the 5 device is shown as adapted for use in connection with a bidet attachment for a water closet bowl, although it will be understood that the use of the device is not so limited as it may be employed to advantage in 10 connection with bath tubs, showers, basins and other similar fixtures. In the use of apparatus of this type, it is desirable to regulate the temperature of the fluid which is preferably water to a desired or predetermined degree. The temperature of the water may be thus regulated by the adjustment 15 of valves leading from hot and cold water supplies or by means of a thermostatic valve connected with similar sources of water supply. In either event it is necessary to dispose of the water passing through the pipe connections until the desired temperature of the water is obtained, and then to divert or transfer the water to its intended purpose. 20 The water thus passing through the pipe connection until the desired temperature is reached may be caused to flow to the bowl or tub or other fixture or to the waste pipe and then by the operation of the device the water 25 is transferred to the fitting for its desired use.

In carrying out the invention the device to which it more particularly relates is so constructed as to be manually operated and 30 manually indicative of the desired temperature so that in the operation of the device the user may readily determine when to divert the water from the waste to the fitting for its intended use. The apparatus furthermore is so constructed that it is normally 35 maintained in an initial position in which the water is permitted to pass through the same to the toilet bowl or other fixture or to the waste pipe and after being operated 40 and released is automatically returned to and yieldingly maintained in its initial position whereby as will be understood if the 45 device is used with water at too low a temperature the natural tendency is to cause its 50 release and thereby prevent a resulting nervous shock due to the contact of the cold water with the body, and likewise, should the temperature of the water be too high the natural tendency is to cause its release and 55 thereby prevent the scalding of the body by contact with water which is too hot.

In the drawing Figure 1 is a diagrammatic plan illustrating the use of the device made in accordance with this invention with a bidet attachment for water closet bowls. 60

Fig. 2 is a central longitudinal section.

Fig. 3 is a transverse section on line 3-3, Fig. 2.

Fig. 4 is an elevation and partial section showing the parts at right angles to the position shown in Fig. 2, and 65

Fig. 5 is a section on line 5-5, Fig. 4.

As shown in the drawing the device made in accordance with this invention preferably includes a casing or body 10. In a suitable 70 position the body 10 is provided with an inlet connection 11 so formed as to provide an inlet chamber 12. In an oppositely disposed position the casing 10 is provided with an outlet connection 13 so formed as to provide an outlet chamber 14. Also in a suitable position the casing is provided with a second outlet connection 15 so formed as to provide an outlet chamber 16. The outlet 13 may be termed a primary outlet connection and the 75 outlet 15 a secondary outlet connection. The outlet chamber 16 communicates with a passage 17 provided by a rib 18 on the casing. As indicated, this rib is preferably angular 80 so as to bring the primary and secondary outlet connections in alignment and to make the necessary provision for the distribution 85 of the water as hereinafter described.

The casing is provided with a cylindrical bore adapted to receive a stem 19. Suitably 90 connected to the stem 19 or made integral therewith there is a handle 20. The stem and handle are constructed to provide passageways therein. To this end in the stem there is a centrally disposed wall 21 extending longitudinally thereof, and likewise in the handle there is a centrally disposed wall 22 making provision for oppositely disposed passageways 23 and 24 extending through the stem and the handle. It will be understood 95 that the handle may be constructed as illustrated or in the form of a coil or otherwise. 100

In the casing 10 there is an inlet port 25 and in an oppositely disposed position a 105 discharge port 26. In the body of the stem there is an inlet port 27 and in an oppositely disposed position a discharge port 28. When the parts are in the position as indicated in the drawing, the inlet port 27 in the stem 110 registers with the inlet port 25 in the casing and the discharge port 28 in the stem regis-

ters with the discharge port 26 in the casing whereby water supplied to the inlet connection 11 passes through the ports 25 and 27 to the passage 23, thence through the handle to the passage 24, and through the discharge ports 28 and 26 to the outlet connection 13. In the wall of the casing there are also oppositely disposed ports 29 and 30. These are placed at right angles to the ports 25 and 26, and the port 29 is in communication with the inlet chamber 12 and the port 30 with the passageway 17 leading to the discharge chamber 16.

One end of the casing as indicated at 31 is preferably enlarged to make provision for an annular space between the same and the stem to receive a packing 32. The packing is maintained in position to provide a water tight joint by means of a suitable nut 33 turned down on the exteriorly screw threaded end of the casing. At the opposite end the casing is provided with a cap or nut 34 turned down into a recess 35 in order to make a tight joint at this end of the casing. The adjacent end of the stem is preferably of reduced cross section as indicated at 36 and extends into a recess 46 provided therefor in the cap 34 which consequently acts as an end bearing for the same and determines its movement in the direction of the cap.

Extending through this reduced end of the stem there is a pin 37. This pin lies in spaces 38 and 39 formed in the end of the casing within the cap 34. Normally, that is in its initial position the pin at one end bears against the face 40 of the wall 41 and at its opposite end against the face 42 of the wall 43, the walls 41 and 43 being at the end of the casing and defining the extent of the spaces 38 and 39 therein. When in its opposite position the ends of the pin bear against the opposite end faces 44 and 45 of the walls 41 and 43 which thus define the extent of the revoluble movement of the stem by acting as stops for the pin. The stem is normally maintained in its initial position by means of a spring 47. One end 49 of the spring is turned to lie at substantially right angles to the stem, and to extend into a recess 48 provided therefor in the casing, while the other end 50 of the spring is turned to extend longitudinally of the casing and to engage the adjacent surface of the pin 37.

In the use of the apparatus as illustrated in Fig. 1, the inlet connection 11 is connected by means of a pipe 51 to valves 52 and 53 leading from suitable sources of hot and cold water supplies. The primary outlet connection 13 is connected by a pipe 54 to the flushing water inlet connection 55 of a toilet bowl. The secondary outlet connection 15 is connected by a pipe 56 to a set valve 57 for determining the pressure of the water and the set valve 57 connected to a bidet fitting 58 having a bidet nozzle 59

placed on the upper surface of the toilet bowl 60 at the rear thereof.

It will now be understood that in the use of the apparatus the hot and cold water valves may be adjusted and the temperature of the water determined by grasping the handle 20, the valves being adjusted until the desired temperature is attained. In the meantime the water passes from the inlet connection 11 through the handle to the outlet connection 13 and by way of the pipe 54 through the flushing connection to the toilet, then after the desired temperature of the water is obtained the handle 20 may be turned through 90° to divert or transfer the water so as to cause the same to flow from the inlet connection 11 through the handle to the secondary outlet connection 15 and by way of the pipe 56 the set valve 57 and the fitting 58 to the bidet nozzle 59, it being understood that by releasing the handle the stem automatically returns to its initial position thereby re-diverting the flow of the water to the toilet bowl. It will furthermore be understood that as hereinbefore stated, while I have illustrated the apparatus as adapted for use with a bidet fitting for a toilet bowl, it may be used to equal advantage with a bath tub, shower, basin or other fixture. Obviously, a suitable thermostatic valve might be employed instead of the hot and cold water connections as illustrated. Obviously, also, when used in connection with a toilet bowl, the device with the connections as illustrated may be employed for flushing the toilet by simply opening the hot or cold water valves or both of them and that when so used or used in connection with a bath or basin the hot water may be caused to flow into the same for cleansing purposes. Still furthermore, the manner of making the connection from the primary exhaust connection is not material as the water caused to flow until the desired temperature is reached may be carried to the waste pipe or sewer or be disposed of in any other manner.

I claim as my invention:

1. In a fluid transfer device, a casing having an inlet chamber and outlet chambers, a stem mounted in the casing, and means associated with the stem for moving the same, there being a passageway through the stem and the said means and there also being ports making communication between the said inlet chamber and one outlet chamber through the said passageway when the said stem and the means for moving the same are in one position and other ports making communication between the said inlet chamber and another outlet chamber also through the said passageway when the said stem and the means for moving the same are in another position.

2. In a fluid transfer device, a casing having an inlet chamber and outlet chambers, a

stem revolvably mounted in the said casing, and means for turning the said stem, there being a passageway through the said stem and the said means for turning the same and there also being ports making communication between the inlet chamber and one outlet chamber through the said passageway in the stem and the means for turning the same when the said stem and the means for turning the same are in an initial position and other ports making communication between the said inlet chamber and another outlet chamber through the said passageway in the said stem and the means for turning the same when the said stem and the means for turning the same are in another position.

3. In a fluid transfer device, a casing having an inlet chamber and outlet chambers, a stem mounted in the casing, and a handle associated with the same, there being a passageway through the stem and handle and there also being ports making communication between the inlet chamber and one outlet chamber through the said passageway when the handle is in one position and other ports making communication between the inlet chamber and another outlet chamber also through the said passageway when the handle is in another position.

4. In a fluid transfer device, a casing having an inlet chamber and outlet chambers, a stem mounted to turn in the said casing, and a handle connected to the said stem, there being a passageway through the said stem and handle and there also being ports making communication between the inlet chamber and one outlet chamber through the said passageway in the stem and handle when the handle is in an initial position and other ports making communication between the said inlet chamber and another outlet chamber through the said passageway in the stem and handle when the handle is in another position.

5. In a fluid transfer device, a casing having an inlet chamber and outlet chambers, a stem mounted to turn in the said casing, a handle connected to the said stem, there being a passageway through the said stem and handle and there also being ports making communication between the inlet chamber and one outlet chamber through the said passageway in the stem and handle when the handle is in an initial position and other ports making communication between the said inlet chamber and another outlet chamber through the said passageway in the stem and handle when the handle is in another position, and means for normally maintain-

ing the handle and stem in an initial position.

6. In a fluid transfer device, a casing having an inlet chamber and outlet chambers, a stem mounted to turn in the said casing, a handle connected to the said stem, there being a passageway through the said stem and handle and there also being ports making communication between the inlet chamber and one outlet chamber through the said passageway in the stem and handle when the handle is in an initial position and other ports making communication between the said inlet chamber and another outlet chamber through the said passageway in the stem and handle when the handle is in another position, and means for automatically returning and normally maintaining the said stem and handle in an initial position.

7. In a fluid transfer device, a casing having an inlet chamber and outlet chambers, a stem mounted to turn in the said casing, a handle connected to the said stem, there being a passageway through the said stem and handle and there also being ports making communication between the inlet chamber and one outlet chamber through the said passageway in the stem and handle when the handle is in an initial position and other ports making communication between the said inlet chamber and another outlet chamber through the said passageway in the stem and handle when the handle is in another position, a pin associated with the stem, and means coacting between the pin and the casing for normally maintaining the stem and handle in an initial position.

8. In a fluid transfer device, a casing having an inlet chamber and outlet chambers, a stem mounted to turn in the said casing, a handle connected to the said stem, there being a passageway through the said stem and handle and there also being ports making communication between the inlet chamber and one outlet chamber through the said passageway in the stem and handle when the handle is in an initial position and other ports making communication between the said inlet chamber and another outlet chamber through the said passageway in the stem and handle when the handle is in another position, a pin associated with the stem, and a spring coacting between the pin and the casing whereby the stem and handle are automatically returned and normally maintained in an initial position.

Signed by me this 26th day of July, 1926.
